UNITED STATES PATENT OFFICE.

JACOB K. ALTEMUS, OF PHILADELPHIA, PENNSYLVANIA.

YARN-OILING DEVICE.

Application filed December 27, 1924. Serial No. 758,383.

This invention relates to improvements in devices for applying oil to yarns particularly adapted for use in connection with machines for winding yarns upon tubes or caps 5 to be afterward knitted or woven into fabrics.

Heretofore difficulty has been experienced in applying oil to yarn uniformly so that some parts of the yarn wound upon the tube 10 or cap would contain greater or less percentages of oil than other parts thereof, resulting in variations in the length of the knitted web or woven cloth produced from the oiled yarn, and also in other objections.

15 The object of my present invention is to overcome these objections, and I accomplish my object by the provision of a novel, simple and efficient yarn oiling device which will apply the oil uniformly to the yarn at 20 all times.

With the foregoing and related objects in view, my invention consists in the novel construction, combination and arrangement of parts hereinafter described and claimed.

25 In the accompanying drawings, illustrating my invention,

Figure 1 is a sectional elevation of a yarn oiling device embodying my invention.

Figure 2 is a view, partly in section and 30 partly in elevation, of the oil feeding pipe and adjuncts.

Referring to the drawings, 2 designates a supporting bar or rail which may form part of the framework of a yarn winding machine 35 when my invention is employed in connection therewith.

Secured to the bar 2 and extending therefrom is a bracket 3 which may be of any construction, shape and size suitable for its intended purpose. This bracket 3 supports a receptacle for oil 4, which, as herein shown, is in the form of a trough, having round rods or bars 5 connected thereto and extending longitudinally thereof, the trough 40 and rods being shown in transverse section in Fig. 1 of the drawings.

50 Journaled in suitable bearings on the ends of the trough 4 is a shaft 6 which extends longitudinally of the trough and carries an oil delivery roller 7. Part of the periphery of the roller extends into the trough 4 and it is adapted to be submerged in oil 8 therein, and the remainder of the periphery of the roller 7 is exposed above the level of the oil 8.

The shaft 6 and therewith the roller 7 are adapted to be rotated at a constant speed by any suitable mechanical means, and, when they are thus rotated, the exposed portion of the periphery of the roller 7 carries a film 60 of oil supplied to it from the body of oil 8 within the trough 4. As the roller 7 is thus rotated, the yarn 9 to be oiled is drawn over the roller 7 and the forward rod 5 at a uniform rate of speed and in a manner to cause 65 the yarn to bear with slight pressure upon the periphery of the roller 7 and thereby be supplied with oil from the oil film by the exposed part of the roller.

Rising fixedly from the bar 2 is a bracket 70 carrying forwardly projecting arms 11 and 12 having loops 13 and 14 formed therein. Supported within the loops 13 and 14 is an oil reservoir 15, preferably in the form of a glass jar having an opening in the bottom 75 thereof which is closed by a metal head or cap 16 screwed onto a neck 17 formed on the jar 15.

The central portion of the cap 16 is perforated for the reception of the upper end 80 of a pipe 18 which is secured thereto by nuts 19 screwed onto the pipe 18 and clamping the head 16 between packing washers 20 interposed between the nuts 19 and the head 16. The pipe 18 is thus fixedly secured to 85 the head 16 in a manner to communicate with the interior of the jar or reservoir 15.

The pipe 18 extends from the head 16 down into the trough or receptacle 4 laterally of the roller 7. The lower end of the pipe 90 18 opens into the trough 4 through a longitudinal slot 21 formed in a side wall of the pipe. The exterior of the lower end portion of the pipe 18 is screw-threaded and carries a regulating collar 22 and a locking collar 23 screwed onto the same. The regulating collar 22 closes the upper portion of the slot 21 and it is adapted to be screwed up or down on the pipe 18 to vary the height of its lower end which controls the highest 95 point of communication between the pipe 18 and the trough 4 through the slot 21. The locking collar 23 is provided to be screwed tight against the regulating collar 22 to lock it in different positions of adjustment. 100

It will now be understood that oil from the reservoir 15 will be supplied to the trough 4 through the pipe 18 and be maintained at a constant level within the trough 4 substantially at the highest point of com- 110

munication between the pipe 18 and trough 4 through the slot 21, because, as rapidly as the oil level falls below such point of communication, air will be admitted to the reservoir 15 through the slot 21 and pipe 18, permitting oil to flow from the reservoir to the trough 4, and, when the oil within the trough closes such point of communication, oil will cease to flow from the reservoir. It will also be understood that the oil level maintained within the trough 4 may be raised or lowered by adjusting the collar 22 vertically upon the pipe 18.

By raising the oil level within the trough 4, the percentage of oil supplied therefrom to the yarn 9 will be increased, and by lowering the oil level within the trough 4, the percentage of oil supplied therefrom to the yarn will be decreased.

20 When it is desired to refill the jar or reservoir 15, it with the pipe 18, projecting from the head 16 thereon, is removed from the arms 12, the jar 15 is inverted, the head 16 is removed, the jar 15 is refilled, the head 16 25 is returned thereto, and the jar 15 and pipe 18 are returned to the position shown in Fig. 1.

When the invention is used in connection with a yarn winding machine the yarn 9 is 30 drawn from the yarn reel or swift down over

the roller 7 and rod 5 to and through the yarn guiding devices of the winding machine.

I claim as my invention:—

1. The combination of a receptacle for oil, an air tight oil reservoir supported above the receptacle and having a removable cap closing the lower end thereof, and a pipe supported by said cap and communicating with the lower portion of the reservoir and extending downwardly therefrom and constructed to discharge oil into the receptacle and means carried by the pipe and being longitudinally adjustable thereon and constructed to vary the height of the point of communication of the pipe with the receptacle. 45

2. The combination of a receptacle for oil, an air tight oil reservoir supported above the receptacle, a pipe communicating with the lower portion of the reservoir and extending downwardly therefrom and entering the receptacle and having a longitudinally extending slot in the lower end portion thereof providing an oil discharge opening, and a collar longitudinally adjustable on the pipe to vary the height of the point of communication of the pipe with the receptacle. 55

In testimony whereof I affix my signature hereto.

JACOB K. ALTEMUS.
